UNITED STATES PATENT OFFICE.

PAUL KOROKNAY, OF HOUSTON, TEXAS.

SIGNAL LANTERN.

Application filed April 9, 1926. Serial No. 100,836.

My invention relates to lanterns adapted for use on vehicles as signals to drivers of other cars.

The object of the invention is to provide 5 a lantern which is cheap to manufacture and at the same time durable and strong. I wish to provide a structure of lantern of few and simple parts which may be made so economically that it may be furnished to 10 the trade at prices within the reach of everyone, and which may be employed on all makes of cars.

In carrying out my object to devise a lantern which can be made cheaply, I have constructed 15 the parts and arranged the assembly thereof with this object in mind, such arrangement being shown in the accompanying drawings.

Fig. 1 is a horizontal section approximately 20 on the line 1—1 of Fig. 2, but with the lantern housing placed in position. Fig. 2 is a front elevation of the bracket and supporting plate and illustrating the means for securing the housing in place. Fig. 3 25 is a side elevation of the lantern with one housing removed and certain parts broken away. Fig. 4 is a front elevation of the lantern housing. Like numerals of reference designate like parts in all the views.

30 In carrying out my invention, I provide a supporting back plate 1, which may preferably furnish attachment for two separate light housings. I have shown a two housing support having a downward extension 2 thereon. The central portion of the plate is formed with a cross-shaped rib 3 thereon, the outer end of which extends along the forward face of the extension 2 and terminates in an arm 4 having an opening therethrough 35 to receive a bolt 5, by means of which it may be secured to a pair of angular brackets 6, for attachment to a support upon the vehicle.

The plate has two housing supports 7 40 placed symmetrically at each end thereof. Said housing supports are approximately rectangular with one or more light receiving openings 8 therein. The openings have a marginal socket member 9 surrounding the same as shown.

50 The housing construction includes a strip of sheet metal which may be stamped to the proper form in one operation to form the front and sides of the lantern. The sheet metal strip has its central portion cut with two glass receiving openings therein, indi-

cated at 10, in Fig. 4. The sides are bent backwardly from this front portion at an acute angle for attachment to the support 7. The inner ends 12 are bent inwardly and the 60 edges notched at 11 and the notched edge recurved at 13 to form a recess to fit about the sockets 8.

The bent ends 12 are perforated to provide screw receiving openings and similar openings 14 are formed in the supporting plate 7 to receive screws 15. The inner ends of the housing are held against the back plate by a clamping plate 16 of the same dimensions as the supporting plates 7. The clamping plate has two openings 17 to fit over the sockets 9 and is provided with threaded openings to receive the screws 15 to clamp the plate tightly against the ends 12 of the housing. A series of projections 18 are 75 formed on the central line of the clamping plate, said projections being staggered to receive between them the partition plate 19, thus furnishing a support therefor.

The upper and lower walls of the housing 80 are formed by two thin plates of sheet metal 22 and 23 adapted to have engagement with the side walls through a recurved edge 20, shaped to receive an outwardly bent edge 21 formed on the upper and lower sides of the 85 said side walls. The rear ends of the top and bottom plates 22 and 23 are bent inwardly and provided with openings to receive the screws 15, as shown. The top wall has its forward edge fitting beneath the 90 rearwardly turned edge 24 of the front wall. The lower wall has its front edge turned down along the inner face of the said front wall, as shown at 25.

It will be apparent that my lantern may 95 be cheaply constructed and quickly assembled. The supporting plate 1 may be cast in one piece with the attaching arm 4 integral therewith. The arm is made as an extension of the strengthening rib 3 and serves the double purpose of an attachment and as a reinforcing means. The sockets 9 are also cast integrally upon the plate and serve to strengthen the plate. The housing is of few and simple parts easily assembled 100 and clamped in position.

105 It is understood that the light bulbs will be received within the sockets 9 and connected within a light wire circuit in any preferred manner. The lantern may be attached at any point desired and may be operated to show legends within the openings 110

10, such as "right", "left", "stop", and "back", as desired and the lights operated to illuminate the legends required. The glass plates are designated 26 in the drawing and it is contemplated that the forward edge of the partition plate 19 will be received between the upper and lower plates.

Having thus described my invention, what I claim as new and desire to protect by Letters Patent is:

1. A signal lantern comprising a back plate, a reinforcing rib thereon, an extension on said plate, an arm on said extension, said arm being integral with the rib on said plate, an attaching bracket on said arm, housing supports on said plate, light housings on said supports, and means to secure said housings detachably to said supports.

2. A signal lantern comprising a back plate, a reinforcing rib thereon, an extension on said plate, an arm on said extension, said arm being integral with the rib on said plate, an attaching bracket on said arm,

housing supports on said plate, light housings on said supports, said housing comprising a strip of metal forming front and side walls, top and bottom plates, and means to secure said housings detachably to said supports.

3. A signal lantern including a back plate, a central extension thereon, a central reinforcing rib terminating in an arm on said extension, attaching brackets on said arm, light housings on said plate and means to secure said housings detachably thereto.

4. In a signal lantern, a back plate having a central lateral extension, means on said plate and extension to reinforce said plate and also provide an attaching arm therefor, supporting plates at each end of said back plate, sockets formed on said end plates, and separate light housings on each said supporting plate.

In testimony whereof I hereunto affix my signature this 6th day of April, A. D. 1926.

PAUL KOROKNAY.
